UNITED STATES PATENT OFFICE.

SAMUEL H. MERRIDITH AND MELVIN HALDEMAN MERRIDITH, OF WEST LIBERTY, IOWA.

MACHINE FOR WIRING WOOD FENCING.

SPECIFICATION forming part of Letters Patent No. 451,500, dated May 5, 1891.

Application filed January 12, 1891. Serial No. 377,446. (No model.)

To all whom it may concern:

Be it known that we, SAMUEL H. MERRIDITH and MELVIN HALDEMAN MERRIDITH, citizens of the United States, residing at West Liberty, in the county of Muscatine and State of Iowa, have invented certain new and useful Improvements in Machines for Wiring Wood Fencing; and we do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to machines for making wire-and-wood fencing, and aims to provide a machine which will be efficient, simple, and perform its work in a satisfactory manner, and which will be convenient of operation.

The improvement consists in the novel features and the peculiar construction and combination of parts, which will be hereinafter more fully described and claimed, and which are shown in the annexed drawings, in which—

Figure 1 is a top plan view of a machine embodying our improvements, the registering mechanism not being shown. Fig. 2 is a side view of the machine. Fig. 3 is a front view of a twister. Fig. 4 is a detail perspective view of a twister, the parts being separated and arranged in their relative positions. Fig. 5 is a sectional view of the twisting mechanism.

The frame A is suitably constructed to support the operating parts of the machine and retain them in a fixed relation. The reel C for winding the completed fence is located at one end of the frame, and the tension-roller B is arranged at the opposite end thereof, and the twisting and spacing devices are intermediate of the ends of the frame. The spool-frame D, placed close to the tension-roller B, supports the spools of wire d, which form the longitudinal cables between which the pickets are twisted. The twisting-head comprises the side frames E, which are approximately triangular-shaped and placed with their bases on the frame A, the cross-sill E', and the cross-bar E², parallel with the sill E', the

sill and cross-bar being secured at their ends to the side frames E and the twisters. The triangular frames E have their base portions guided by staples e^x on the main frame.

55

The twisting-head is adapted to move longitudinally of the machine on the frame A to permit the insertion of the pickets between the strands of the cables and to force the picket to the proper place between the wires prior to twisting the wires about it. The head may be moved by any convenient mechanical appliances, preferably by the arms e, which are connected at their upper ends with the tread and at their lower ends with the rock-shaft e', which is journaled in the frame A. One end of the rock-shaft e' is extended and the operating-lever e² is attached thereto. In order that the twisting-head may move on the frame A in straight lines, the arms e are connected therewith by the links e³, as shown.

The twisters F are journaled in the blocks or frames G, that are mounted on the cross-sill E', and the cross-bar E², being adjustable on the latter, and held thereon in the located position by binding-screws g and g', respectively. The twisters are caused to revolve together by suitable gearing, such as the sprocket-chain H, which passes around the sprocket-teeth on the twisters, motion being imparted to the end twister by the bevel-gearing h and h' and the crank-shaft h², the latter being journaled in the brackets h³, which project from the extended end of the cross-sill E'. The twisters are each composed, essentially, of three parts—the sprocket-wheel f, the apertured heads f², and the notched disks f', the notches in the latter being provided in pairs and of varying depth, the notches of each pair being of like depth and diametrically opposite each other. The sprocket-wheel is centrally disposed between the heads f² and the disks f' f', the parts being secured together by the bolt f³. 95

The heads f² are provided at diametrically opposite points with slots or openings f⁴, corresponding in length with the depth of the deepest notches in the disk f', to permit the wires to occupy the proper position. It will be seen that by the use of twister-heads of this construction the wires may be changed 100

from one set of notches in the disks f' to another by simply loosening the bolt f^3 and turning the disk f' to the proper point to admit the wires to the proper set of notches, 5 after which the parts may again be secured in place by retightening the bolt, and it will also be seen that the twister-head will be thus readily adapted for use with varying widths of pickets, as where narrow pickets are used 10 the wires would be placed within the deeper notches in the disk, and when wide pickets are used the wires would of course be placed in the shallower notches.

The spacing mechanism is composed of the 15 shaft I , provided with arms i and journaled in the brackets J , which are secured at their inner ends to the twisting-head. The outer bent end i' of the shaft I is connected with the horizontal arm of the elbow-lever i^2 , that 20 is pivoted to the upper end of the operating-lever e^2 . The outer ends of the arms i are hook-shaped to ride over the pickets and engage with the edge thereof facing away from the twister. The brackets J are adjustable, 25 being composed of two overlapping pieces, which are slotted and held together by a bolt passing through the slots in the pieces. By having the brackets adjustable the position of the shaft I can be changed relative to the 30 twisting-head to adapt the machine to different widths of pickets or to space pickets of like width at different distances apart.

The reel C is made in two parts, between 35 which the end of the fence is clamped, and is journaled in the open brackets K on the frame A , being held in the brackets by the pin k . The sprocket-wheel k' on the projected end of the reel C is connected by the sprocket-chain k^2 with the sprocket-pinion l on the 40 shaft L , the latter being operated by the crank l' , which is loosely mounted on the shaft L , and which is provided with the pawl l^3 , that is adapted to engage with the ratchet-wheel l^2 , keyed on the shaft L . By this arrangement 45 the crank l' will hang down out of the way when not in use. The shaft L is prevented from turning back by the detent-pawl l^5 on the frame engaging with the ratchet-wheel l^4 thereon.

50 The guide-roller M , over which the completed fence passes, is just eighteen inches in circumference, whereby when it has made eleven complete revolutions it will have measured one hundred and ninety-eight inches, or 55 one rod. The cam m , consisting of a circular disk eccentrically pivoted on the extended end of the guide-roller, operates the lever m' , to which the pawl m^2 is attached, that operates the ratchet-wheel m^3 , having only eleven 60 teeth. The tail of the lever is acted upon by the spring m^4 , attached to the same and to the standard m^5 , and a bail m^6 , rigidly attached to the lever, acts upon the said pawl m^2 , which is loosely pivoted to the pivot-pin 65 of the said lever. The ratchet-wheel m^3 makes one complete revolution to every eleven revolutions of the guide-roller M . Hence each

revolution represents one rod of fencing. The registering-disk m^5 , which is normally held against rotation by friction, is moved forward 70 one tooth at each complete revolution of the ratchet-wheel m^3 by the arm or projection m^6 on the ratchet-wheel m^3 , engaging therewith. The pointer m^7 indicates the proper number upon the disk m^5 . The disk m^5 and ratchet-wheel m^3 are journaled on a standard m^8 , as 75 seen in Fig. 2.

The operation of the machine is as follows: The wires N are passed through the staples n at the end of the frame and around the tension-roller B and through the staples n' , through the proper twisters, over the guide-roller, and have their ends clamped between the halves of the reel. The pickets are inserted endwise between the wires which comprise the cable, the twisting-head being previously drawn back, and are pressed forward into proper position by moving the twisting-head forward, the wires being twisted about the picket by operating the twisters through 85 the instrumentalities hereinbefore specified. After the picket has been bound by the wires the shaft L is operated to give motion to the reel to wind the fence thereon and draw the wires through the twisters. The twisting-head is again drawn back, a second picket is 90 inserted between the wires, the head moved forward, and the hooked arms i engaged with the picket previously bound, in order to properly space the picket to be bound and 95 hold the twister-head in proper position during the process of twisting the wires. By operating the lever i^2 the arms i are disengaged from the pickets when winding the fence on the reel. The frictional contact of 100 the fence with the guide-roller rotates the latter and operates the registering mechanism. Obviously there may be as many twisters on the twisting-head as required, and they can be adjusted to space the cables the required distances apart. The twisters are adjustable to varying thicknesses or widths of pickets by loosening the bolt f^3 and turning the disks f' so as to register with the slots in the heads f^2 , as described. 105

Having thus described our invention, what we claim to be new, and desire to secure by Letters Patent, is—

1. In a fence-machine, the combination, with a twisting-head movable lengthwise of 110 the machine, the main frames, and guides, of the picket-spacing device comprising the shaft I and hooked arms i , elbow-lever i^2 , and operating-lever, to which the elbow-lever is pivoted, connected with the said twisting-head, substantially as described.

2. The combination, with the twisting-head and the adjustable brackets J , secured to the twisting-head, of the shaft I , journaled in the brackets and having the hooked arms i , 115 the operating-lever, and the elbow-lever connecting the same with the said shaft, substantially as and for the purpose described.

3. In a fence-machine, the combination,

with the twisting-head and the reel, of the guide-roller having a cam at one end, the wheel m^3 , having teeth and a projection, the lever and pawl for operating the wheel from the said cam, and the registering-disk m^5 , operated by the projection on the wheel m^3 , substantially as described.

4. In a fence-machine, the combination, with the twisting-head movable longitudinally of the main frame and in guides therein, and the shaft I, having the hooked arms i , carried by the said head, of the rock-shaft e' , the arms e , connected with the rock-shaft and with the said twisting-head, the operating-lever e^2 , and the lever i^2 , connected with the shaft I and mounted on the lever e^2 , substantially as described.

5. In a fence-machine, the combination, with the twisting mechanism and the reel

having a sprocket-wheel k' on its projected end, of the shaft L, having the pinion l , sprocket-chain k^2 , connecting said sprocket-wheel and said pinion, the crank l' , loosely mounted on the shaft L and having a pawl l^3 , the ratchet-wheel l^2 , operated by the pawl l^3 , and the detent l^5 , pivoted to the frame, and the ratchet-wheel l^4 on the shaft L, substantially as described.

In testimony whereof we affix our signatures in presence of two witnesses.
